(57) **CLAIM**

The ornamental design for a three dimensional game board as shown and described.

DESCRIPTION

FIG. 1 is a perspective view of a three dimensional game board incorporating the design;

FIG. 2 is a front view of the three dimensional game board of FIG. 1;

FIG. 3 is a back view of the three dimensional game board of FIG. 1;

FIG. 4 is a top view of the three dimensional game board of FIG. 1;

FIG. 5 is a bottom view of the three dimensional game board of FIG. 1;

FIG. 6 is a left view of the three dimensional game board of FIG. 1;

FIG. 7 is a right view of the three dimensional game board of FIG. 1;

FIG. 8 is a perspective view of a first plate of the three dimensional game board of FIG. 1;

FIG. 9 is a left view of the first plate of the three dimensional game board of FIG. 8;

FIG. 10 is a right view of the first plate of the three dimensional game board of FIG. 8;

FIG. 11 is a top view of the first plate of the three dimensional game board of FIG. 8;

FIG. 12 is a bottom view of the first plate of the three dimensional game board of FIG. 8;

FIG. 13 is a front view of the first plate of the three dimensional game board of FIG. 8;

FIG. 14 is a back view of the first plate of the three dimensional game board of FIG. 8;

FIG. 15 is a perspective view of a second plate of the three dimensional game board of FIG. 1;

FIG. 16 is a top view of the second plate of the three dimensional game board of FIG. 15;

FIG. 17 is a bottom view of the second plate of the three dimensional game board of FIG. 15;

FIG. 18 is a left view of the second plate of the three dimensional game board of FIG. 15;

FIG. 19 is a right view of the second plate of the three dimensional game board of FIG. 15;

FIG. 20 is a back view of the second plate of the three dimensional game board of FIG. 15; and,

FIG. 21 is a front view of the second plate of the three dimensional game board of FIG. 15.
